(57) **CLAIM**

The ornamental design for a stylus pen as shown and described.

DESCRIPTION

1. Stylus pen
- 1.1 : Perspective
- 1.2 : Front
- 1.3 : Back
- 1.4 : Top
- 1.5 : Bottom
- 1.6 : Left
- 1.7 : Right

The design of the present application is made of synthetic resins; The shape of the upper part is a square cylinder with each corner curved, the shape of the lower part is a cylinder and the shape between the upper part and the lower part has a shape that naturally changes from the square cylindrical shape to the cylindrical shape; The design prevents rolling; A wavy line groove is formed in the upper part.
